(57) **CLAIM**

The ornamental design for a motorcycle shock absorber cover, as shown and described.

DESCRIPTION

FIG. 1 is a front elevational view of a first embodiment of the motorcycle shock absorber cover of my new design;

FIG. 2 is a side view of the left side thereof;

FIG. 3 is a top view thereof;

FIG. 4 is a side view of the right side thereof;

FIG. 5 is a bottom view thereof;

FIG. 6 is a rear elevational view thereof;

FIG. 7 is a front elevational view of a second embodiment of the motorcycle shock absorber cover of my new design;

FIG. 8 is a side view of the left side thereof;

FIG. 9 is a top view thereof;

FIG. 10 is a side view of the right side thereof;

FIG. 11 is a bottom view thereof; and

FIG. 12 is a rear elevational view thereof; and,

FIG. 13 is a side view of the motorcycle shock absorber cover on a reduced scale on a motorcycle while in use.

The broken lines of the ornamentation on the motorcycle shock absorber cover in FIGS. 1 through 13 and of the motorcycle in FIG. 13 are shown for illustrative purposes only and form no part of the claim.

The hook and loop fasteners and pattern of lines indicating material, which are partially shown, are understood to repeat uniformly on the surfaces where shown.
